I. Van Hagen,
Oil Can,
No 16,501. Patented Jan. 27, 1857.

UNITED STATES PATENT OFFICE.

ISAAC VAN HAGEN, OF NEW YORK, N. Y.

IMPROVEMENT IN OIL-CANS.

Specification forming part of Letters Patent No. **16,501**, dated January 27, 1857.

To all whom it may concern:

Be it known that I, ISAAC VAN HAGEN, of the city, county, and State of New York, have invented certain new and useful Improvements in the Construction of Oil-Cans for Oiling Machinery; and I do hereby declare the following to be a full, clear, and exact description thereof, reference being had to the accompanying drawings, in which—

Figure 1 is a sectional elevation. Fig. 2 is a cross-sectional view of the spout.

The oil-can to which my devices are particularly advantageous are those with very long spouts, such as are used on locomotives, and for like purposes where long spouts are indispensable; but my device can also be applied to shorter spouts. I have found by practical experiment that if a long spout is used, and it is stopped by a valve at its lower end, or that next the can, the bore must be very small or the spout will drip oil after it is stopped, and it is therefore important that the tube should be of the smallest practicable size; but it will be noticed that so long a tube would soon be bent and spoiled in the rough usage to which it is submitted if made so slim as is absolutely necessary not to waste oil. To avoid this I envelop the small tube in a larger one, of conical form, sufficiently broad at the base next the can to resist the rough usage to which it must be submitted, and this envelope is permanently affixed at the base and at its apex, where it connects with the small tube. This forms a light and firm structure for the purpose intended. Again, it is important, too, that the tube should at all times be open, except when it is necessary to stop the flow of oil through it, for if this is not the case the small tube is liable to become clogged by the oil chilling in it in cold weather, and in warm, if the oil remains long in the tube, it becomes viscid and corrodes and stops the flow through the tube, which on such occasions it is very difficult to clean, if not impossible. The further advantages of my can I will name in the description of its construction.

The construction is as follows: I form a can, A, of any pattern, onto which the spout B screws. This spout B, made of tin, copper, or other suitable metal, is composed of two

parts, the inner one, b, being a small tube, of equal diameter, or nearly so, affixed at its lower end to the screw a, by which it is attached to the can. A hole is made through the screw a into the tube the size of the bore thereof, and a conical valve-seat is therein formed, as clearly shown in the drawings. Around the tube b is a conical tube, which envelops and surrounds the tube b, extending nearly out to its end, where it is firmly united to the inside tube, b. Its base is fastened to the rim of the screw a, which is a little larger than said base. In this way I secure great strength and lightness and protection against blows and other injuries. A valve, C, is placed within the body of the can, which will stop the lower opening of the tube b by fitting into the valve-seat. This valve C has its stem loosely jointed to the end of a lever, C', the position of which is at right angles with the stem, as clearly represented in the drawings. The fulcrum of this lever is at x, supported by an attachment to the inside of the can. The other end of the lever is affixed to a short piston-rod, f, which projects up through a hole made therefor in the top of the can to a little distance above the handle, passing in its way through a little chamber, in which there is a spiral spring that holds the rod f. Upon the top of the rod there is a button or thumb-piece, e, and a hole is made down through the button and rod, which serves as an air-hole or ventilator to the can, which is covered and stopped when the thumb is pressed upon it, to actuate the valve C and stop-tube b. It will be noted that the valve C is loose, so that it will adjust itself to the valve-seat whether it remains straight, as in the drawings, or gets bent out of line by hard usage, so that its action is as perfect even after the can is somewhat damaged by wear at all times. When the valve is stopped, the can is relieved of the pressure of the atmosphere by closing the air-hole of the thumb-piece if the can is otherwise tight.

The operation is as follows: When the can is turned so as to discharge the oil through its spout, the flow can be instantly checked and entirely stopped by bearing upon the thumb-piece, which first stops the flow of air into the can, and then closes the valve. When the can

is turned up and the thumb removed, the valve falls and the oil in the tube runs back into the can, and the tube is kept clear in all temperatures and when out of use for any time.

What I claim, and desire to secure by Letters Patent, is—

The double tube B b, the loose valve C, and

ventilator thumb-piece e, constructed, arranged, and combined in the manner and for the purposes set forth.

ISAAC VAN HAGEN.
